UNITED STATES PATENT OFFICE.

BENNETT ROBY PAINE, OF HAMDEN JUNCTION, OHIO.

DESIGN FOR A BOTTLE.

SPECIFICATION forming part of Design No. 29,318, dated September 6, 1898.

Application filed July 22, 1898. Serial No. 686,637. Term of patent 14 years.

To all whom it may concern:

Be it known that I, BENNETT ROBY PAINE, a citizen of the United States, residing at Hamden Junction, in the county of Vinton and State of Ohio, have invented and produced a new and original Design for a Bottle, of which the following is a specification, reference being had to the accompanying drawings, which form a part thereof, and in which—

10 Figure 1 is a perspective view of my newly-designed bottle, and Fig. 2 a longitudinal central vertical section thereof.

As shown in the drawings, the leading or material feature of my design consists of a 15 bottle or similar vessel A, which is triangular in cross-section, two of the sides B thereof being similar in shape and the ends C, which are triangular in form, being slightly flared

outwardly and upwardly in such manner that the side D, which constitutes the top of the 20 bottle or vessel, is slightly longer than the bottom E, and said top or side D is provided with a central circular opening F.

Having fully described my invention, what I claim as new, and desire to secure by Letters 25 Patent, is—

The design for a bottle as herein shown and described.

In testimony that I claim the foregoing as my invention I have signed my name, in presence of the subscribing witnesses, this 11th day of July, 1898.

BENNETT ROBY PAINE.

Witnesses:

J. T. STEPHENSON,
T. R. JONES.
